US00D929227S

(12) **United States Design Patent** (10) **Patent No.:** **US D929,227 S**
(45) **Date of Patent:** **** Aug. 31, 2021**

(54) **POURING DEVICE FOR A BOTTLE**

(71) Applicant: **POURA LTD.**, Welwyn Garden City (GB)

(72) Inventor: **Dominic Limbrey**, Chislehurst (GB)

(73) Assignee: **POURA LTD.**, Welwyn Garden City (GB)

(**) Term: **15 Years**

(21) Appl. No.: **29/631,732**

(22) Filed: **Jan. 2, 2018**

(30) **Foreign Application Priority Data**

Jul. 7, 2017 (EM) 004093581-0001

(57) **CLAIM**

The ornamental design for a pouring device for a bottle, as shown and described.

DESCRIPTION

FIG. 1 is a front view of a pouring device for a bottle of the present invention;

FIG. 2 is a first side (left side) view thereof;

FIG. 3 is a second side (right side) view thereof;

FIG. 4 is a rear view thereof;

FIG. 5 is a perspective view thereof;

FIG. 6 is a top view thereof; and,

FIG. 7 is a bottom view thereof.

The broken lines depict portions of the pouring device for a bottle that form no part of the claimed design.

1 Claim, 7 Drawing Sheets
